UNITED STATES PATENT OFFICE.

ABIRAM HOPPINS, OF KINGSTON, ONTARIO, CANADA.

CUTTER-HEAD.

SPECIFICATION forming part of Letters Patent No. 331,970, dated December 8, 1885.

Application filed June 26, 1885. Serial No. 169,860. (No model.)

To all whom it may concern:

Be it known that I, ABIRAM HOPPINS, a citizen of the United States, residing at Kingston, in the Province of Ontario and Dominion of Canada, have invented certain new and useful Improvements in Cutter-Heads; and I do hereby declare the following to be a full, clear, and exact description of the invention, such as will enable others skilled in the art to which it appertains to make and use the same, reference being had to the accompanying drawings and letters of reference thereon, forming a part of this specification.

Similar letters of reference refer to like parts throughout the several views.

This invention relates to certain new and useful improvements in cutter-heads used for the purpose of dressing lumber and grooving the same, such lumber being designed for sheathing the interior walls of a building, and providing the necessary recesses or clings by means of which the mortar is secured in place. As lumber comes from the saws of saw-mills it varies slightly in thickness, and it is necessary in its use for sheathing to reduce it to a uniform thickness.

Heretofore it has been customary to plane the lumber on a planing-machine, and then transfer it to a machine provided with rotary saws carried by arbors inclined in opposite directions, or with grooving-knives, which form dovetailed recesses in the boards. This has necessitated the second handling of the lumber—that is, once to the planer and again to the grooving-machine. This extra handling takes time, and consequently adds to the cost of the finished lumber.

The object of my invention is to improve upon the former constructions, and to provide a cutter-head by the use of which the board is planed and grooved by one and the same operation; and to those ends, and to such others as the invention may pertain, the same consists in the peculiar combinations and the novel construction and arrangement of parts, as hereinafter more fully described, and then specifically defined in the claims.

In the accompanying drawings, Figure 1 is a cross-section on the line x x of Fig. 3, Fig. 2 is a side view of one of the planing and grooving cylinders. Fig. 3 is a detail showing the manner of securing the grooving-cut-

ters to the arm of the cylinder; and Fig. 4 is a detail showing the manner in which the planing-knives are secured.

My improved cutter-head is composed of a cylindrical body having formed integral therewith and radiating therefrom, as shown, four arms, d e f g . These arms are of the same length as the body, extending lengthwise thereof and parallel with each other, but their depth—that is, the distance from the center to their outer surface—gradually diminishes from one end toward the other, thus forming a cutter-head of gradual taper from end to end.

Adjustably secured to the arms g are the planing-knives F G , which are also removably secured thereto, while to the arms d f are adjustably and removably secured a series of grooving-cutters, H I . The grooving-cutters are secured to their arms by bolts h , having a square head passed through the T-shaped groove i in the arm, and provided with a nut, k , the grooving-knife being slotted longitudinally, as shown. By this means the grooving-cutters can be adjusted lengthwise of the arm to place the cutters nearer together or farther apart, according to the desired distance between the grooves, and they can also be adjusted in a direction at right angles to the length of the arm, so as to cut a groove of greater or less depth, as required; or they can be readily removed when it is desired to simply plane the board without cutting the grooves.

The planing-knives are secured to their arms by bolts l passing through slots m in the knives, so that they may be adjusted at right angles to the length of the arm to plane off more or less, or so that they can be removed when it is desired to groove the boards without planing them.

Motion is imparted to the cylinders in any convenient manner. I have shown a belt on but one end of the shaft; but I sometimes use a belt on each end.

I do not limit myself to the exact construction shown and described, as it is evident that the same may be varied to a certain extent without departing from the spirit of my invention.

I am aware of the Patent No. 311,679, and make no claim to the construction shown therein as forming a part of my invention.

I attach importance to the tapering form of my cylinders and the arms thereof which carry the planing-knives and grooving-cutters, for the tapering form adapts the cutter-head for use on inversely-inclined shafts for the purpose of forming dovetailed grooves while the board is being planed. A cutter not having this tapering feature could not be used on inversely-inclined shafts to produce this result. Another advantage of the tapering form of cylinder is that the cut of the plane is diagonally across the face of the board instead of directly across the grain, as is the case when cutter-heads of the ordinary form of construction are used. The end of the cylinder having the greater diameter will cut in advance of the smaller end, thus insuring smoother and better work.

It will be seen that the planing-knives act upon the principle of the ordinary rabbet-plane.

Having thus described my invention and set forth its merits, what I claim as new, and desire to secure by Letters Patent, is—

1. A cutter-head of gradual taper from end to end, and carrying one or more planing-knives and one or more grooving-cutters se-

cured thereto at right angles to the axis thereof, substantially as and for the purpose specified.

2. A cutter-head having a cylindrical body and radial arms formed integral with said body and extending the entire length thereof, but gradually tapering from one end of the cylinder to the other, and one or more planing-knives and one or more grooving-cutters carried by alternate arms and adjustable thereon, and the whole adapted to serve as and for the purposes specified.

3. The cutter-head described, composed of a cylinder having radial arms, as *e f d g*, gradually decreasing in length from one end of the cylinder to the other, and said arms provided with planing-knives and grooving-cutters, said knives being removable and adjustable both laterally and longitudinally, substantially as and for the purposes specified.

In testimony whereof I affix my signature in presence of two witnesses.

ABIRAM HOPPINS.
